UNITED STATES PATENT OFFICE.

CHARLES COESTER, JR., OF BRIDGEPORT, CONNECTICUT.

TOY.

SPECIFICATION forming part of Letters Patent No. 324,233, dated August 11, 1885.

Application filed March 25, 1885. (No model.)

To all whom it may concern:

Be it known that I, CHARLES COESTER, Jr., of Bridgeport, in the county of Fairfield and State of Connecticut, have invented a certain 5 new and useful Improvement in Toys, of which the following is a specification.

My toy is made in the form of a living creature or other article. The trunk is composed of detachable sections normally held together, 10 so that they can be easily separated—as, for instance, by friction—and provided with a receptacle for a fire-cracker. The explosion of the fire-cracker separates the sections and produces the appearance of a living creature 15 blown to pieces. A string may connect the sections, so as to prevent any of them from being lost.

In the accompanying drawings, Figure 1 is a front view of a toy embodying my improvement, and made to represent a man. Fig. 2 20 is an edge view thereof, and Fig. 3 is a transverse section taken through the junction of the trunk-section.

Similar letters of reference designate corresponding parts in all the figures.

A and A' designate two sections forming the trunk portion of the man, and A'' designates a head-section. All these parts may be cheaply made of flat pieces of wood; but they obviously 30 need not be flat. Each of the trunk-sections is provided with a leg, a, and arm a'. The legs and arms are preferably pivotally connected to the trunk-sections.

In this example of my improvement the 35 trunk-sections are not directly connected together; but they are severally provided with jaw-like neck portions b, that receive within them the neck portion c of the head-section. The head-section is fitted so snugly into the 40 trunk-sections as to be friction-tight. It is thus secured to them and fastens them together.

In the trunk-sections is a cavity, d, forming a receptacle for a fire-cracker. This cavity is 45 made partly in each trunk-section. It may be

just below the head-section, or considerably below the same, as shown, extending transversely thereto. Indeed, it may be made lengthwise of the trunk-sections, as indicated by the dotted lines d', and then a hole, d'', will 50 be left for the protrusion of the stem of the fire cracker. When it extends transversely, it may advantageously be made oblique, as shown, for then, without making the trunk-sections excessively thick, a considerable 55 length of the fire-cracker may be accommodated in them.

When the fire-cracker, after ignition, explodes, the trunk-sections and the head-section will be forced apart and the appearance of a 60 man exploding will be produced.

The improvement may be carried out in toys representing other living creatures or articles.

A string, D, may advantageously be connected to the several sections to prevent them from being so greatly separated by explosions as to be liable to loss. The string may be secured to the sections by small staples e.

The toy may stand on a support or be suspended by a cord, E.

What I claim as my invention, and desire to secure by Letters Patent, is—

1. A toy composed of sections secured together, so that they can be easily separated, 75 and having a cavity for a fire-cracker, substantially as specified.

2. A toy composed of sections secured together by friction, and provided with a cavity for a fire-cracker, substantially as specified. 80

3. A toy composed of sections secured together so that they can be easily separated, having a cavity for a fire-cracker, and a string connecting them, substantially as specified.

CHARLES COESTER, JR.
